UNITED STATES PATENT OFFICE

SOLOMON WISE, OF SHAKER HEIGHTS, OHIO

DESIGN FOR A LOCK

Application filed December 16, 1931. Serial No. 42,102. Term of patent 14 years.

To all whom it may concern:

Be it known that I, SOLOMON WISE, a citizen of the United States, residing at Shaker Heights, county of Cuyahoga, and State of Ohio, have invented a new, original, and ornamental Design for Lock, of which the following is a specification, reference being had to the accompanying drawings, forming a part thereof, in which—

I claim:—

The ornamental design for a lock, substantially as shown.

SOLOMON WISE.
